[57] CLAIM

The ornamental design for a heat deflector for a fireplace, or similar article, substantially as shown and described.

DESCRIPTION

FIG. 1 is a rear isometric view of a heat deflector for a fireplace, or similar article, showing my new design. FIG. 2 is a top plan view of the heat deflector for a fireplace, or similar article, drawn to an enlarged scale. FIG. 3 is a left side elevational view of FIG. 2.

FIG. 4 is a right side elevational view of FIG. 2.

FIG. 5 is a lower end elevational view of FIG. 2, the upper end elevational view being a mirror image thereof.

FIG. 6 is a bottom plan view of FIG. 5.
